UNITED STATES PATENT OFFICE.

WILLIAM BARTHOLOMEW, OF CHICAGO, ILLINOIS, ASSIGNOR TO TROY LAUNDRY MACHINERY COMPANY, LTD., A CORPORATION OF NEW YORK.

CYLINDER WASHING-MACHINE.

1,151,993.

Specification of Letters Patent. Patented Aug. 31, 1915.

Application filed December 2, 1912. Serial No. 734,540.

To all whom it may concern:

Be it known that I, WILLIAM BARTHOLOMEW, a citizen of the United States, residing at Chicago, in the county of Cook and 5 State of Illinois, have invented certain new and useful Improvements in Cylinder Washing-Machines, of which the following is a specification.

My invention relates in general to laundry machinery, and more particularly to cylinder washing machines.

In the use of cylinder washing machines the clothes or other articles to be washed are placed in the cylinder which is then 15 revolved within the inclosing tank which contains the suds in the bottom thereof. It is necessary that all portions of the articles should be subjected to the suds in order that they may be thoroughly cleansed. 20 To accomplish this it is desirable that as the cylinder revolves through the suds in the bottom of the tank, the suds should be forced through the cylinder into contact with the articles, and also that the suds 25 should be carried upwardly by the surface of the cylinder so as to flow downwardly through the cylinder upon the articles therein. The articles are therefore not only subjected to the suds forced through the 30 lower portions of the cylinder as it passes through the suds, but also to the suds falling upon them from the upper surface of the cylinder. It is further desirable that the foregoing actions should occur when 35 the cylinder is rotated in either direction so that all portions of the articles may be the more thoroughly exposed to the suds.

The primary object of my invention is to provide a cylinder for washing machines 40 in which the articles will be thoroughly subjected to the action of the suds, not only by effectively forcing the suds through the portion of the cylinder passing through the suds, but by scooping some of the suds 45 up and carrying them to a point above the articles so that they will fall upon them within the cylinder.

A further object of my invention is to provide a cylinder for washing machines 50 in which the inclosed articles will be thoroughly subjected to the action of the suds without danger of injury to the articles, and which will be simple in construction and durable in use.

My invention will be more fully disclosed 55 hereinafter with reference to the accompanying drawing in which the same is illustrated as embodied in a convenient and practical form, and in which—

Figure 1 is an elevational view of a cylinder embodying my invention, the same being shown as removed from the tank and with the central portion thereof broken away; Fig. 2, a transverse sectional view through the lower portion of the cylinder 65 shown in Fig. 1; and Fig. 3, a detail sectional view.

The same reference characters will be used to designate the same parts in the figures of the drawing. 70

Reference character A indicates one of a number of staves forming the cylindrical wall of the cylinder of a washing machine. The ends of the staves A are secured around the peripheries of the two cylinder heads 75 B, B. The ends of the staves may be securely connected with the peripheries of the cylinder heads in any suitable manner, as by hoops b, b which surround the ends of the staves and clamp them tightly to the 80 cylinder heads, as shown in Fig. 3.

Intermediate of a plurality of staves are located longitudinal bars C which serve to rigidly connect the cylinder heads B so as to impart to the cylinder the requisite 85 structural strength. The bars C project inwardly from the inner surface of the staves A so as to form ribs which serve to carry the wet articles with the cylinder as it rotates a distance above the bottom of the 90 cylinder so that the articles will fall back by gravity and thereby be turned over and thoroughly exposed to the suds.

D, D designate trunnions projecting axially outwardly from the cylinder heads 95 B which are adapted to engage bearings in the ends of the tank for rotatably supporting the cylinder. As neither the manner of supporting the cylinder nor the construction of the inclosing tank form parts of my 100 present invention, they need not be disclosed. Fixed to one of the trunnions is any suitable means for communicating rotary motion to the cylinder, such for instance as a gear E, which is adapted to be driven 105 by any suitable power connections. Several of the staves A are connected to strap hinges F' and F² so as to form an out-

wardly swinging door to permit access to the interior of the cylinder for the insertion and removal of the articles.

f' and f^2 designate any suitable fastening devices for retaining the cover in closed position and for permitting the cover to be opened. Preferably the stave at the free end of the door upon which the latches are mounted is made imperforate so as to possess greater structural strength.

My invention consists essentially in the structure of the staves A and in their relation to each other. It will be observed that each stave A is provided with parallel inner 15 and outer surfaces, the intermediate longitudinal portions of such surfaces being substantially flat while the side longitudinal portions of such surfaces are inclined inwardly, as indicated at A' and A^2 . A series 20 of spaced holes a' and a^2 are formed through the inwardly inclined side portions of the staves, the holes in the two side portions of each stave converging so as to extend at an angle to the planes of the outer 25 surfaces of the inwardly inclined side portions. The adjacent edges of adjoining staves are preferably slightly spaced apart so as to permit of the expansion and contraction of the staves due to their wet or 30 dry condition, the staves being preferably formed of wood.

By reference to Fig. 2, it will be seen that the adjacent inwardly inclined side portions of adjoining staves form longitudinal 35 grooves on the outer surface of the cylinder and longitudinal inwardly projecting ribs on the inner surface of the cylinder.

The operation of my improved cylinder for washing machines is as follows: When 40 the cylinder is rotating in the direction of the arrows indicating the section line 3—3 in Fig. 2, the holes a^2 will by reason of the inward inclination of the side portions A^2 of the respective staves, and by reason of 45 their inclination toward the longitudinal center of the staves, permit a more ready forcing of the suds through the lower portion of the cylinder into contact with the inclosed articles. The longitudinal grooves 50 formed on the outer surface of the cylinder between adjacent staves by reason of the inward inclination of the side portions of the staves, serve to carry the suds with the cylinder to points above the clothes so that 55 the suds will then flow through the holes in

the staves upon articles inclosed in the cylinder. The longitudinal ribs formed upon the inner surface of the cylinder between adjacent staves serve to produce a rubbing effect upon the articles as they are 60 rolled about in the cylinder during its rotation, thereby expediting the cleansing of the articles without injury to them.

From the foregoing description it will be observed that I have invented an improved 65 cylinder washing machine which will efficiently subject the articles to the suds in the bottom of the tank and also to suds which flow upon the articles from above, owing to the surface of the cylinder being such as 70 to carry the suds with it in its rotation. It will also be observed that the construction of the inner surface of my improved cylinder is such as to produce a rubbing action upon the articles, and to turn them 75 over so as to thoroughly subject them to the action of the suds.

I claim:

1. In a cylinder for washing machines, the combination with cylinder heads of 80 spaced longitudinal bars connecting said heads, a plurality of staves intermediate of adjacent bars and connected to said heads, each of said staves comprising a flat longitudinal central surface, and inwardly inclined longitudinal side surfaces having inwardly converging holes extending through them.

2. In a device of the character described, the combination with cylinder heads, of 90 staves secured to the heads and each comprising a longitudinal central surface and inwardly inclined longitudinal side surfaces, the two side surfaces having inwardly converging holes extending through 95 them.

3. In a device of the character described, the combination with cylinder heads, of a plurality of staves having their interior adjacent surfaces inclined inwardly to form 100 longitudinal ribs between adjacent staves, said ribs having openings extending from the exterior to the interior of the cylinder.

In testimony whereof, I have subscribed my name.

WILLIAM BARTHOLOMEW.
